[57] ABSTRACT

Given a group of radioactive concentrates including a concentrate from a resin-bead ion exchange filter, a concentrate from an evaporation concentrator, and a concentrate from another concentrator yielding a concentrate having a salt content lower than that of the concentrate from the evaporation concentrator and particles smaller than the particle size of the resin beads; a process including mixing the concentrate from the resin-bead ion exchange filter with the concentrate from the other concentrator, passing the resulting mixture through a filter-cake-producing filter for dewatering and drying, and skirting the concentrates from the evaporation concentrator around the filter-cake-producing filter and directly into transport and storage vessels for their dewatering in such vessels.

TREATMENT PROCESS

BACKGROUND OF THE INVENTION

The present invention relates to a method for decreasing the liquid content of radioactive concentrates.

As described in the article "Abfallbehandlung (in translation - Waste Treatment)," which appeared in the November, 1965, issue of *Atomwirtschaft*, pages 624-626, processing of radioactive liquid wastes, for instance those occurring in nuclear power plants, is usually done in three parts:

1. Filtration through mechanical filters with the filtrate being then passed through ion exchangers;
2. Concentration in evaporators;
3. Filtration only through mechanical filters.

The first-listed part is used for the waste waters from the nuclear cooling system and from the condensation system (these waters make up 60 percent to 70 percent of the total waste-water load).

The second-listed part is used for sump waters, laboratory waste waters, and decontamination waters from the entire control region (about 20 percent to 30 percent of the total waste-water load).

The third-listed part is used for cleaning wash waters from washing machines, showers, and hand-washing basins, as well as inactive laboratory waters from the control region (about 5 percent to 10 percent of the total waste water-load).

From these water-processing steps and other cleaning operations large amounts of radioactive concentrates arise. Efficient service organizations for collecting and treating these concentrates do not exist. A storing of these concentrates in liquid form is presently not possible. The processes used in Europe for handling these concentrates involve the use of additive materials such as bitumen, concrete, oil shale ash, and bone size. These add to the total volume of the final material to be disposed of. They have often required too great of a capital investment.

The storing of these concentrates for the purpose of allowing radioactive decay to run its course requires considerable capital expense, especially where waste quantities are large, such as in the case of large power plants. It therefore becomes worthwhile to dewater and solidify such concentrates.

In efforts thus far made toward dewatering and solidification, a number of problems have arisen which have to this time prevented widespread acceptance. Among the problems are the following:

1. The concentrates occurring are very variable in their compositions. A primary problem here is that waste waters from resin-bead ion exchange filters can not be dewatered with a usual filter-cake-producing filter, because the resin beads as a result of their shape do not remain lying on the filter cloth or septum especially once their moisture content has sunk below a certain level. Because of this problem, filter-cake-producing filters have been automatically dropped from consideration whenever a concentrate containing resin beads must be dewatered.

2. The concentrates occurring have very different activity loads.

3. The dewatered and solidified material must satisfy current governmental requirements for the storage of radioactive wastes.

4. The packaging must meet the requirements for the transport of dangerous materials as set for international railroad freight traffic.

SUMMARY OF THE INVENTION

An object of the present invention, therefore, is to provide a simple process for the treatment of radioactive concentrates arising in the above-listed parts.

Another object is to produce a minimum waste concentrate volume, which lacks additive materials.

Yet another object is to produce with especially small capital and operational costs a much drier radioactive waste residue than heretofore.

Yet another object is to produce a dry residue which can be cheaply transported and stored in containers.

These as well as other objects which will become apparent in the discussion that follows are achieved, according to the present invention, in the following manner. Given separate concentrates from an evaporation concentrator, from a resin-bead ion exchange filter system, and from at least one other concentrating stage, for instance from mechanical filters, settling basins, and/or powdered-resin ion exchange filters, that from the one other stage being characterized by a smaller particle size than that from the resin-bead ion exchange filter and by a lower salt content than that from the evaporation concentrator, the concentrate from the resin-bead ion exchange fiber is mixed with the concentrate from the other stage and the resultant mixture is then fed to a filter-cake-producing filter for dewatering and drying, while the concentrate from the evaporation concentrator is skirted around the filter-cake-producing filter, without its passing through the filter-cake-producing filter or in any way coming into contact with the filter cake of the filter-cake-producing filter, directly into transport and storage containers where it is brought to the desired dryness for storage. In the mixture, the ratio of the one other concentrate to the resin-bead concentrate must be at least a certain minimum value such that the resin beads do not fall out of the drying filter cake.

It has been discovered that this mixing of the concentrate from the resin-bead ion exchange filter with the concentrate from the one other concentrator has the particularly advantageous result that when the mixture is fed to the filter-cake-producing filter, the resin beads become bedded into the resulting filter cake and their dewatering and drying therefore becomes possible without their falling from the filter cloth or septum once their moisture content has sunk below a certain level. Consequently, only the relatively small volume of concentrate from the evaporation concentrator needs to be dried using the more costly, heat-energy consuming method of evaporating the remaining liquid from the concentrate.

The nuclear power plants Wurgassen, Brunsbuttelkog and Phillipsburg are being prepared to use the present invention.

The feeding of the concentrate from the evaporation concentrator to the filter-cake-forming filter which processes the mixture of resin-bead concentrate and one other concentrate is not practicable, because the high salt content in the concentrate from the evaporation concentrator would cause the filtrate to achieve such a high salt concentration that it could not be recirculated into the works without the expensive further treatment of reducing this high salt content.

BRIEF DESCRIPTION OF THE DRAWING

The sole FIGURE of the drawing is a process schematic in an example of the present invention.

DESCRIPTION OF THE PREFERRED EMBODIMENTS

The schematic diagram of the FIGURE illustrates a treatment plant for practicing the present invention on the waste concentrates from a large light-water nuclear power plant 80 using a boiling water reactor manufactured by AEG-Telefunken. Container 1 carries concentrate entering through pipeline 45 and resulting from condensate cleaning. Container 2 collects concentrate from pipeline 46 resulting from mechanically filtering the wash waters coming from the entire control region. Container 3 has a resin-bead concentrate from mixed bed ion exchange filters entering through pipeline 47. Containers 4 and 5 contain concentrate resulting from cleaning the reactor water. Container 6 collects the concentrate from an evaporation concentrator, as contrasted with containers 1 to 5 whose concentrates result from filtering operations.

Exemplary data concerning the concentrate compositions of the various containers is given in Tables I to 25 III.

TABLE III.—COMPOSITION OF EVAPORATION CONCENTRATION (ALKALINE pH OF ABOUT 10)

1. Composition of the solids (at 20° C.)
Amount of solids = 8.3 g./100 ml.

Name	Chemical formula	Particle size	Fraction in wt. percent
Sodium sulfate	Na ₂ SO ₄ , granular	About 20 μ	11
Calcium sulfate	CaSO ₄ , granular	About 20 μ	40
Heavy metal oxides	E.g. Fe ₂ O ₃ (primarily) plus CuO, granular.	12-60 μ *	18*
Calcium phosphate	Ca ₃ (PO ₄) ₂ , flocculent	10-100 μ	30*
Calcium-, silicon-, aluminum-oxides or calcium- and aluminum-silicates (concrete dust).	CaO-SiO ₂ , Al ₂ O ₃ , granular.	10-100 μ	10*

2. Composition of the dissolved material
Evaporation residue = 8.27 g./100 ml.

Name	Chemical symbol	Fraction in wt. percent
Sodium	Na	Up to 20*
Magnesium	Mg	Up to 10*
Calcium	Ca	Up to 20*
Potassium	K	Up to 2*
Sulfate	SO ₄	Up to 80*
Chloride	Cl	Up to 30*
Iron	Fe	Up to 20*
Copper	Cu	Up to 6*
Nickel	Ni	Up to 2*

*Approximate values, $\mu=10^{-6}$ meters.

TABLE I.—CONCENTRATE COMPOSITIONS

Concentrate	Relative slurry volume, m. ³	Solids in slurry, kg.	Period*, days	Solids type
1. Filter concentrates:				
(a) Container 1:				
Normal operation	74	3,000	100	Powdered resin with corrosion products.
Cooling water break-in	74	3,000	10	Do.
(b) Containers 4 and 5	10	20	5	Do.
(c) Container 2	4.5	144	1	See Table II.
(d) Container 3	8	3,000	90	Do.
2. Evaporation concentrate: Container 6	2.5	**360-620	10	See Table III.

*Period is defined as the normal supply period of the concentrates.

**Evaporation residue.

TABLE II.—FILTER CONCENTRATE COMPOSITIONS (NEUTRAL OR SLIGHTLY ALKALINE)

Name	Chemical identity and form; wt. percent	Particle size	Distribution in wt. percent	Relative amount in any given concentrate in wt. percent
Kieselguhr filter aid, Celite 545	SiO ₂ , 89.6%, Al ₂ O ₃ , 4.0%, Na ₂ O and K ₂ O, 3.3%, granular.	{ 2-6 μ 6-10 μ 10-20 μ 20-40 μ 40-60 μ 60 μ	{ 1% 5% 18% 52% 16% 3%	Up to 55%.
Activated carbon filter aid, Synofils, Solkaflocken BW 100	Comminuted charcoal, granular. Fine cotton hairs.	10-300 μ		Up to 15%. Up to 10%.
Heavy metal hydroxides or hydrated oxides.	{ Fe(OH) ₃ * Mn(OH) ₃ * Co(OH) ₃ * Ni(OH) ₃ * Cr(OH) ₃ * Dispersed hydroxides.	60 μ	96% mainly iron.	Up to 50%.
Mixed bed filter resins	Carbonyl synthetic resin ion exchanger, bead shaped.	{ 1-20 μ 1.2 mm 0.8-1.2 0.34-0.8	{ 4% mainly chromium and nickel. 1% 15% 83% 1%	Up to 30%.
Powdered resin	Comminuted mixed bed filter material.	0.05 mm		Up to 100%.
Calcium-silicon and aluminum oxides or calcium and aluminum silicates.	CaO-SiO ₂ +Al ₂ O ₃ , granular (concrete dust).	20-100 μ		Up to 100%.
Dust and small amounts of oil (where { (Soot) $\mu=10^{-6}$ meters).	Oil.			Up to 1%. Up to 0.1%.

*Flocculent.

The concentrates in containers 1, 2, 4 and 5 have a salt content lower than that of the concentrate in container 6 and particles of a size smaller than the particle size of the resin-beads in container 3.

The concentrates of containers 1 through 5 can be fed to the intermediate storage container 9 through pipelines 60 to 67 by concentrate pumps 7 and 8. Pipelines 60 to 64 include individually controllable valves 72 to 76 so that any desired mixture can be obtained in container 9.

Stirrer 10 serves to mix the concentrates fed into container 9. From container 9, the resulting mixture is fed through pipeline 69 by pump 68 to a filter-cake-producing filter 11. This filter 11 is made of a number of plate-shaped elements 13 carried by a vertical, hollow shaft 12. Filter cake forms on the upper sides of the plates. The filtrate is drawn off through the hollow shaft 12 and pipelines 34, 38 and 39 and drained into storage vessels or passed to further water treatment and then recycled.

An example of filter 11 is a steam heated filter obtainable under the designation "Fundarueckstandsfilter" R10 from Chemap AG, Maenndorf/Zuerich, Alte Landstr. 414. Another example of filter 11 is that described on pages 19-72 and 19-73 of "Chemical Engineers' Handbook," by John H. Perry, McGraw-Hill Book Co., New York (4th Ed., 1963) under the heading "The Rodney Hunt Pressure Filter."

In order to prevent radioactive solids from getting into the filtrate, filter 11 is first provided with a precoat of fibrous material, such as cellulose fiber, before actual filtration begins. To this end, there is provided a precoat tank 14 connected in an auxiliary circuit. The fibrous material is first thoroughly mixed with water in the precoat tank; then this fiber-laden water is pumped by pump 37 into the filter while a suction is being applied to shaft 12, whereby the precoat is formed on the filter cloths or Septa of the elements 13. An example of a suitable fibrous material is clean, fibrous cellulose material designated as Type BW 100 (cotton fibers of 1 millimeter length). During drying, this cotton fiber precoat gives an effect equal to a paper filter and acts to filter out aerosols.

The cotton fibers are added to water in tank 14 until they amount to 3 to 4 weight-percent of the weight of the water. A homogenizing period during which the fiber-water mixture is circulated through the filter and the precoat tank via pipelines 34, 35, and 36 by pump 37 assures a uniform precoat layer thickness of about 0.8 millimeters.

The solids in container 9 can only contain up to 25 weight-percent resin beads from container 3. Exceeding of this limit leads to an unstable filter cake from which the resin beads can fall during dewatering and drying. Under this limit, the resin beads become securely embedded with the other waste solids in the filter cake and are held there throughout dewatering and drying.

When an economical filter cake load has been built up on elements 13, any remaining, unfiltered slurry remaining in filter 11 is circulated back to container 9 through pipeline 44 and dewatering and drying is then carried out in a two-phase process. First, the excess water is blown out of the filter cake with a flow of 20° C air equal to a flow rate of 200 standard cubic meters per hour per square meter of filter area, where the conditions for the standard cubic meter are 0° C and 760

mm Hg. When the removal of liquid water has substantially ceased, the filter cake is dried with a flow of 120° C air equal to a flow rate of 70 standard cubic meters per square meter of filter area per hour.

Air is brought into filter 11 by blower 22 through conduits 41 and 42 and 43. Electrical air heater 23 raises the temperature of the air for the second phase of the dewatering and drying process. Air is exhausted through lines 34 and 38 and conduit 40. Air cooler 24 removes any condensable components from the air before it reaches exhaust chimney 33.

The dried filter cake is removed from elements 13 by rotating shaft 12 by means of motor M at 300 r.p.m. The filter cake is flung centrifugally from the elements 13. Below filter 11 there is a residue bin 15 through which the dried filter cake from the filter 11 is conducted into containers 16. The bulk density of the dried powdered filter cake in the container 16 lies between 0.65 and 0.8 t/m^3 , where $t = 1,000\text{kg}$ and $m = \text{meters}$.

10 The air used during the two-phase dewatering and drying may be passed through an air filter to remove any suspended solids before exhausting it to the atmosphere.

15 The relatively small volumes of concentrate coming through pipeline 58 into container 6 from the evaporation concentrator are conducted directly from container 6 through pipeline 59 into transport and storage containers 17 which have been previously attached to drying hood 18. The concentrate flow from container 6 is stopped when level indicator 19 indicates that a predetermined concentrate level has been achieved.

20 Hood 8 contains infrared radiators which heat the concentrate in a container 17 from above. Air flow within the hood is controlled so that it passes over the liquid surface of the concentrate and withdraws vapor as it is produced by the radiators. A thermally caused circulating of the liquid concentrate in a container 17 prevents premature crusting on the sides of the container. Maintenance of the air flow within the hood and over the surface of the concentrate makes the hood and container interior have a negative pressure, so that no vapors can escape through any leaks at the connection between hood and container.

25 When no liquid level remains, a post drying period is initiated to bring the moisture down to less than 30 weight-percent of the total weight of dry residue. This moisture content is generally sufficient to prevent indications of fermentation and decay and to reduce the possibility of corrosion sufficiently that the filled containers can be stored for years without developing leakages. The bulk density of the powdered residue left in container 17, lies between 0.8 and 1.5 t/m^3 , where $t = 1,000\text{ kilograms}$ and $m = \text{meters}$.

30 This procedure for handling evaporation concentrates is presently being used in an installation at the AEG Nuclear Energy Experimentation Center Grosswelsheim. The installation can process 10 to 20 liters of evaporation concentrate per hour.

35 Air flow through hood 18 comes in from conduit 30 and has been heated by heater 31. Exhaust air laden with vapor leaves through conduit 32. The exhaust air is passed through a combined cyclone/sand filter unit 20 to remove any solid or liquid particles and is then forwarded by airtight blower 21. The exhaust air then passes through dry air cooler 24, where any condensable components are removed, and thence to exhaust chimney 33. Condensate and rinse water from the cyclone/sand filter are returned to container 6.

A suitable container 16 and 17, together with lid, is set forth on page 94 of the journal "Atompraxis", Vol. 16, No. 2, 1970.

Since the concentrate resulting from cleaning the reactor water often exhibits higher radioactivities, special containers are provided for the collection. At least two containers 4 and 5 are always provided, so that alternatively one and then the other can be filled, through pipelines 57 and 55 and valve 77, and through pipelines 57 and 56 and valve 78. This allows an optimum storage time to be selected for allowing radioactive decay to proceed partially before the concentrates are forwarded to container 9 from the container 4 or 5 which at the moment is not being filled.

The containers 1-5 are sedimentation tanks, so that it is possible to allow a more complete sedimentation of solids within them and to forward the cleared waters directly to further water processing through pipelines 48 to 54 using pumps 70 and 71, without passing them through filter 11. This operates to reduce the work load of filter 11. The water forwarded through pipeline 53 by pump 70 goes to the sump system of the plant, while the water forwarded through pipeline 54 by pump 71 goes to the mixed bed ion exchange filters. "Filter-cake-producing filters" is used herein to distinguish from those filters which operate exclusively by ion-exchange capture of the substance to be filtered out.

It will be understood that the above description of the present invention is susceptible to various modifications, changes and adaptations and the same are intended to be comprehended within the meaning and range of equivalents of the appended claims.

We claim:

1. A method for removing liquid from radioactive concentrates from a nuclear plant, comprising the steps of: mixing a resin-bead, radioactive concentrate of said plant from a resin-bead ion exchange filter with a radioactive concentrate of said plant having particles of a size smaller than the particle size of the resin-beads of said ion exchange filter; dewatering and drying by pass-

ing the resulting mixture through a filter-cake-producing filter; the step of mixing producing a mixture wherein the ratio of the smaller-particle-size concentrate to the resin-bead concentrate is sufficiently large than the resin beads remain stably emplaced in the resulting cake on the filter even after the cake is dry; skirting a radioactive evaporation-concentrator-produced concentrate of said plant of salt content higher than that of the smaller-particle-size concentrate around the filter-cake-producing filter and directly into transport and storage vessels; and dewatering and drying in the transport and storage vessels the concentrate from the evaporation concentrator down to a water content required for storage.

15 2. A method as claimed in claim 1, the filter-cake-producing filter comprising a plurality of plate-shaped elements carried by a vertical hollow shaft means for removing filtrate, filter cake forming on the upper sides of the plate-shaped elements during filtering, further comprising the step of coating on the elements a pre-coat of fibrous material for filtering out radioactive solids.

3. A method as claimed in claim 2, the fibrous material being cellulose fiber.

20 4. A method as claimed in claim 2, the step of coating being additionally for filtering out aerosols during drying.

5. A method as claimed in claim 1, further comprising, before the step of dewatering and drying by passing, the step of settling solids from the concentrates.

30 6. A method as claimed in claim 1, the step of mixing being performed in an intermediate storage container having a means for mixing concentrates fed into it.

7. A method as claimed in claim 1, the smaller-particle-size concentrate having a relatively high radioactivity, further comprising the steps of filling this smaller-particle-size concentrate sequentially into a plurality of containers and performing the step of mixing with the concentrate from the earliest-filled of said 40 plurality.
